UNITED STATES PATENT OFFICE.

CHRISTOPHER WHITNEY, OF FRANKLINVILLE, NEW YORK.

COAL-SCUTTLE.

SPECIFICATION forming part of Letters Patent No. 459,619, dated September 15, 1891.

Application filed May 15, 1891. Serial No. 392,878. (No model.)

To all whom it may concern:

Be it known that I, CHRISTOPHER WHITNEY, a citizen of the United States, residing at Franklinville, in the county of Cattaraugus and State of New York, have invented certain new and useful Improvements in Coal-Scuttles; and I do declare the following to be a full, clear, and exact description of the invention, such as will enable others skilled in the art 5 to which it appertains to make and use the same.

My invention has relation to improvements in coal-hods of that class in which a hood is employed to prevent the coal from being spilled from the sides of the hod while being poured from the mouth thereof; and it has for its object to provide a hod of the character stated embodying an exceedingly cheap, simple, and durable construction, comprising but three elements which, while thoroughly adapted to perform the function stated, will not interfere in any manner with the filling of the hod.

My improvements afford a hood for a coal-hod, which is of such a form and is so arranged with respect to the hod and the bail thereof as to close the hod from the bail to the mouth of said hod while the hod is being carried, but which will be swung back and will wall in the rear portion of the hod when 20 the bail is swung down upon the back thereof, as is commonly done in pouring coal from the mouth of the hod. Furthermore, it will be understood that my improvements provide a hood which is applicable to hods having either 25 straight or bulging side walls.

My invention will be fully understood from the following description and claim when taken in connection with the accompanying drawings, in which—

40 Figure 1 is a perspective view of the hod, the bail being illustrated in an upright position and the hood covering the hod from the bail to the mouth thereof. Fig. 2 is a vertical longitudinal section illustrating the bail tilted rearwardly and the hood in its corresponding position.

Referring by letter to the said drawings, A indicates a hod, which may be of any approved form such as at present in use, and B indi-

cates an ordinary pivotally-mounted bail, 50 which may be provided with a suitable hand-grasp, as illustrated.

C indicates my improved coal-hod hood, which is preferably formed from a single piece of metal, is tapering in width, and of a length 55 corresponding to the distance between the mouth of the hod and the pivotal point of the bail. This hood C, which is of a form substantially as shown and is adapted to cover the hod from the mouth thereof to the pivotal point of the bail when said bail is upright and to lap over the sides of the hod, has its rear open end of a height corresponding to the distance between the rear end of the hod and the pivotal point of the bail, whereby it 60 will be seen that when said bail is swung back, as is commonly done when pouring coal from the hod, the hood will cover the rear portion of the hod and prevent the coal from spilling over the sides thereof. The connection between the bail and the hood is effected by metal loops or eyes D, which have their ends connected to the sides of the hood at the rear end thereof and embrace the bail, as 65 better illustrated in Fig. 1 of the drawings. 70

By the construction described it will be seen that the hod may be filled while the bail is in an upright or horizontal position, and that the coal may be readily poured from the mouth of the hod without any interference 75 from the improved hood described.

It will further be seen that by the employment of my improved hood the capacity of the hod is increased—that is to say, the hod is adapted to carry more coal without the 80 same spilling over the sides thereof.

Having described my invention, what I claim, and desire to secure by Letters Patent, is—

The combination, with a coal-hod and the bail pivotally connected to said hod, of a hood formed from a single piece of metal tapering in width and of a length corresponding to the distance between the mouth of the hod and the pivotal point of the bail, said hood 90 having its rear open end of a height corresponding to the distance between the rear end of the hod and the pivotal point of the 95

bail, and a suitable means for attaching the rear end of the hood to the bail, whereby when the bail is upright the hood will close the front portion of the hood and when said bail is horizontal the said hood will wall up the rear portion of the hood and leave the mouth thereof entirely unobstructed, substantially as and for the purpose described.

In testimony whereof I affix my signature in presence of two witnesses.

CHRISTOPHER WHITNEY.
